UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,332, dated October 10, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design. A branching stem runs irregularly over a plain background, and bears upon it, closely filling the entire ground of the design, various small

flower and leaf like figures of irregular forms and sizes and shapes, as shown in the accompanying photograph. The effect produced is that of a ground closely filled with small interlocking groups and figures, just enough space being left between the figures to set out their forms.

I claim—

The design for carpets, substantially as shown and described.

WINTHROP L. JACOBS.
